UNITED STATES PATENT OFFICE

CORNELIUS M. MURPHY, OF COLERAINE, MINNESOTA

CABLE STORAGE

Application filed December 29, 1927. Serial No. 243,462.

This invention pertains to cable storage conveyors, and more particularly to cable conveyors for electric shovels.

In the operation of cutting tools, electric shovels and the like in open pit mines, it is customary to furnish power to the tools from a substation, located near the center of distribution from which the current is carried to the tools by a portable cable or conduit or other device of suitable design. As the tool proceeds along its working cut, it is of course necessary to provide additional lengths of cable, which has heretofore been done by mounting a reel on the rear of the tool on which the desired length of conduit was wound. This, however, is not entirely satisfactory on account of the difficulty of supporting a reel of the necessary capacity because of its size and lack of suitable mounting space, especially with revolving shovels to be used in constricted cuts.

It is therefore an object of this invention to provide a convenient, inexpensive and safe traveling cable supporting carrier which fulfills all requirements of manufacture and service.

Another object is to provide a conductor carrier for operating tools which enables the conductor to be so disposed that the tools may be readily used and operated to and in restricted points or cuts.

A further object is to provide a traveling conductor carrier for operating tools which permits ready pay off of the conductor and one which provides a protection and guard for the conductor and/or any adjacent individuals or objects.

With these and various other objects in view, the invention consists of certain novel features of construction and operation as will be more fully described and particularly pointed out in the specification, drawings and claims appended hereto.

In the drawings, wherein like reference characters are used to designate like parts—

Figure 1 is a side elevation of a cable boat assembly, which is the subject-matter of this invention;

Figure 2 is a top plan view of the cable boat with a portion of the top cut away, showing

the mounting of the conductor therein; and

Figure 3 is a transverse vertical section through the cable boat and top, the same being taken substantially in the plane as indicated by the line 3—3 of Figure 1.

The cable boat 10, preferably of steel, consists essentially of a base or cable carrying floor including cross-members 11, preferably longitudinally reinforced by means of runners 12 of any suitable shape, shown as T-bulbs, the same being curved upwardly at their forward ends 13 and curved slightly upwardly at their after ends 14 to insure easy sliding of the boat in operation. Steel sides 15 are secured to the floor and braced by spaced transversely and vertically extending stanchions 16 extending substantially to the top of said sides, each of the sides being provided along the top edge thereof with a transversely projecting roof supporting member 17. The forward and after ends of the boat are preferably open or semi-open, the forward end being provided with a cable guard 18 of any suitable material adapted to direct the cable to the operating tool.

The sides are further provided with brackets 19 secured at the forward end and attached to the tool preferably by means of adjustable chain connections 20. Suitable links or brackets 21 may also be provided on the sides at selected places along the length of the boat for the purpose of lifting the boat to facilitate its transportation or manipulation. Hook shaped brackets 22 may be secured at the after end of the sides adjacent the top for the purpose of engaging the rear edge of the roof to prevent the same from being detached from the boat, leaving the conductor 29 unprotected.

The roof or top 23 may be of any construction, such as pointed or ridged as shown, the same being overlapping with respect to the sides 15 and provided with suitably positioned angle members 24 adapted to cooperate with the members 17 to transversely position said roof. The roof may be of any ply and provided with transverse straps 25 and longitudinally extending lifting handles 26, said roof being preferably finished by forward and after sloping portions 28 and 27.

The cable or conductor 29, it is understood, is secured at one end 30 to the point of energy transmission such as a substation, said cable being coiled a suitable number of times within the boat to provide the desired length of cable, the tool end 31 of said cable extending through the cable guard and forwardly to the tool.

In operation then, it is only necessary to direct the tool along any cut desired, the tool dragging the boat along with it and the cable paying out of the after end of the boat. It will be seen that this construction is very satisfactory and is very practical as the cable is completely guarded both by the sides and the roof which exclude rain and snow as well as protect any individuals adjacent thereto from coming into contact with the cable.

It is to be understood that I do not wish to be limited by the exact embodiment of the device shown, which is merely by way of illustration and not limitation, as various and other forms of the device will of course readily occur to those skilled in the art.

I claim:

1. In a cable boat, the combination of a cable carrying base, means on said base permitting ready movement of said boat in either direction, sides and top for said boat for retaining and protecting said cable, and a guard for said cable provided on one end of said boat.

2. In a cable boat, the combination of a cable carrying base, spaced means longitudinally disposed on said base permitting ready movement of said boat in either direction, sides and removable cover for partially enclosing said boat and retaining the cable, a cable guard provided at the forward end of said boat to direct the cable to a tool, and coupling means for attaching said boat to said tool.

3. In a cable boat, the combination of a cable carrying base adapted to carry looped and flatly disposed cable, spaced means longitudinally disposed on said base permitting ready movement of said boat in either direction, sides and removable cover for partially enclosing said boat and retaining the cable, the forward and after ends of said boat being open, the cable being adapted to pay off said after end on forward movement of said boat, a cable guard provided at the forward end of said boat to direct the cable to a tool, and coupling means for attaching said boat to said tool.

4. In a device of the character described, the combination of a conductor carrying support, runners disposed on said support and each having an upturned end, and means disposed at one end of said support for directionally supporting a portion of the conductor.

5. In a device of the character described,

the combination of a conductor carrying support, runners disposed on said support and each having an upturned end, means disposed at one end of said support for directionally supporting a portion of the conductor, and protection means carried by said support for said conductor.

6. In a device of the character described, the combination of a conductor carrying support, runners disposed on said support and each having an upturned end, means disposed at one end of said support for directionally supporting a portion of the conductor, and means for securing said device to a cutting tool or the like whereby said device moves therewith.

7. In a device of the character described, the combination of a conductor carrying support, runners disposed on said support and each having an upturned end, means disposed at one end of said support for directionally supporting a portion of the conductor, protection means carried by said support for said conductor, and means for securing said device to a cutting tool or the like whereby said device moves therewith.

8. In a device of the character described, the combination of a conductor carrying support, runners disposed on said support and each having an upturned end, and means carried by the upturned ends of certain of said runners for directionally supporting a portion of the conductor.

9. In a device of the character described, the combination of a conductor carrying support, runners disposed on said support and each having an upturned end, means carried by the upturned ends of certain of said runners for directionally supporting a portion of the conductor, protection means carried by said support for said conductor, and means for securing said device to a cutting tool or the like whereby said device moves therewith.

10. In a device of the character described, the combination of a conductor carrying support, spaced vertically and longitudinally extending guard members disposed at the sides of said support, runners disposed on said support, said runners having upturned ends, one of said upturned ends extending to points adjacent the top of said guards, and means carried by the upturned ends of certain of said runners for directionally supporting a portion of the conductor.

11. In a device of the character described, the combination of a conductor carrying support, spaced vertically and longitudinally extending guard members disposed at the sides of said support, runners disposed on said support, said runners having upturned ends, one of said upturned ends extending to points adjacent the top of said guards, and means carried by the last named upturned ends of

certain of said runners for directionally supporting a portion of the conductor.

12. In a device of the character described, the combination of a conductor carrying support, spaced vertically and longitudinally extending guard members disposed at the sides of said support, runners disposed on said support, said runners having upturned ends, one of said upturned ends extending to points adjacent the top of said guards, means carried by the last named upturned ends of certain of said runners for directionally supporting a portion of the conductor, and a top for said device having portions fitting within said guard members and said last named upturned ends.

13. In a device of the character described, the combination of a conductor carrying support, spaced vertically and longitudinally extending guard members disposed at the sides of said support, runners disposed on said support, said runners having upturned ends, one of said upturned ends extending to points adjacent the top of said guards, means carried by the last named upturned ends of certain of said runners for directionally supporting a portion of the conductor, guide members carried by said guard members and said last named upturned ends adjacent the top thereof, a top for said device having portions fitting within said guard members and said last named upturned ends, securing members carried by said guard members and cooperating with said top, means carried by the upturned ends of certain of said runners for directionally supporting a portion of the conductor, and means for securing said device to a cutting tool or the like whereby said device moves therewith.

40 Signed at Coleraine, Minnesota, this 16th day of December, 1927.

CORNELIUS M. MURPHY.
